UNITED STATES PATENT OFFICE

148,797

DESIGN FOR A BRAKE DRUM TRUING MACHINE

George E. Klassett, Atlanta, Ga.

Application July 20, 1945, Serial No. 120,835

Term of patent 14 years

(Cl. D55—1)

To all whom it may concern:

Be it known that I, George E. Klassett, a citizen of the United States of America and a resident of the city of Atlanta, county of Fulton, State of Georgia, have invented a new, original, and ornamental Design for a Brake Drum Truing Machine, of which the following is a specification, reference being had to the accompanying drawing, forming a part thereof.

In the drawing,

Figure 1 is a perspective view of the brake drum truing machine, showing my new design.

Fig. 2 is a perspective view from a different angle than Fig. 1 and with some movable parts in a slightly different position.

Fig. 3 is a vertical section in the plane of line 3—3, Fig. 2.

I claim:

The ornamental design for a brake drum truing machine, substantially as shown.

GEORGE E. KLASSETT.
